UNITED STATES PATENT OFFICE

153,158

DESIGN FOR A TABLECLOTH OR SIMILAR ARTICLE

Mary Cresser McGee, Hempstead, N. Y.

Application March 23, 1948, Serial No. 145,287

Term of patent 3½ years

(Cl. D92—26)

To all whom it may concern:

Be it known that I, Mary Cresser McGee, a citizen of the United States of America, residing in Hempstead, county of Nassau, and State of New York, have invented a new, original, and ornamental Design for a Tablecloth or Similar Article, of which the following is a specification, reference being had to the accompanying drawing, forming part thereof, wherein,

The figure is a plan view of a tablecloth, showing my new design.

I claim:

The ornamental design for a tablecloth or similar article, substantially as shown.

MARY CRESSER McGEE.
